UNITED STATES PATENT OFFICE.

HENRY GREBE, OF OMAHA, NEBRASKA.

HAY-GATHERER.

SPECIFICATION forming part of Letters Patent No. 272,237, dated February 13, 1883.

Application filed June 26, 1882. (Model.)

To all whom it may concern:

Be it known that I, HENRY GREBE, of Omaha, Douglas county, Nebraska, have invented a new and useful Improvement in Hay-Gatherers, of which the following is a full, clear, and exact description.

This invention relates to certain improvements in my new and improved hay-gatherer shown and described in Letters Patent No. 217,609, which were granted to me July 15, 1879; and it consists in providing the side gates with slotted sweep-bars, in combining with the side gates, pivoted upon blocks, stay-plates attached to posts and pivoted to the head having the aforesaid blocks, and in the slide having end stops, and with the seat standard or upright capable of adjustment upon either end, substantially as hereinafter more fully set forth.

Reference is to be had to the accompanying drawings, forming part of this specification, in which similar letters of reference indicate corresponding parts in all the figures.

Figure 1 is a perspective view of my improved hay-gatherer. Fig. 2 is a detailed perspective view, showing the wooden sweep-bars; and Fig. 3 is a like view, showing the pivoted posts and the metal sweep-bars riveted thereto.

A represents the head of the gatherer; and B B represent the teeth, which are secured to the under side of the head A by means of the metal plate C, the same as in my original patent. At the ends of the head A, upon the upper side thereof, are secured the blocks D D. The side gates, E E, are pivoted upon these blocks by means of the bolts a a, which pass through the center or near the center of the horizontal bottom bars, b b, of the gates and through the said blocks and the head A at the ends, as shown in Fig. 1. The side gates are stayed to the head A by means of the plates g g, secured to the lower ends of the central uprights, f f, and pivoted upon the lower ends of the bolts a a. These plates turn upon the pivots a, when the gates are turned, to reverse the direction of movement of the gatherer. The rear posts, H H, of the gates are made short, as shown in Fig. 1, to clear the head A when the gates are turned.

The sweep-bars G G in Figs. 1 and 3 are sheet metal or leather, and are attached to the rear posts, H H, by means of the staples i i,

the same as in the original patent. In case the sweep-bars G G are made of sheet metal, instead of using the posts H H and the staples i i, I may pivot between the rear ends of the upper and lower bars, b b, of the gates the metal posts or plates J, to which the ends of the sweep-bars may be secured by rivets or bolts. Instead of using the sheet-metal or leather sweep-bars G G, as above described, and as described in my original patent, I may use the wooden sweep-bars G' G'. These bars will be slotted, as shown at j j, and will be attached to the rear ends of the gates by means of the rods k k, passing through the rear ends of the bars b b of the gates and through the said slots, as shown in Fig. 2, the slots being of sufficient length to permit the gates to be reversed, carrying the sweep-bars backward, sweeping the hay, straw, or other material off from the teeth of the gatherer.

L represents the seat, which in this construction is adapted to be held in either end of the board N. This board is held loosely between the head A and the plate C, as shown in Fig. 1, and is adapted to slide endwise between the bar and plate, so that the seat L may be held by it upon either side of the head A, according to the direction the gatherer is being drawn. The endwise movement of the board is limited by the blocks p p, secured upon the board at its ends, and these blocks are bored, as shown at s s, to receive the lower end of the standard l of the seat.

Instead of attaching the board N to the gatherer, as just described, by placing it between the head A and the plate C the same might be hinged to or pivoted to the head or otherwise attached so as to be reversed according to the movement of the gatherer and still involve the principle of my invention.

To the forward end of the draw-bars m m of the side gates, E E, are attached, by means of the pins t t, the clevis-hooks T T. These hooks are formed of the members t' t', by which the clevis is attached to the draw-bars and the hook w, which is turned up, and stands, when the clevis is in place, in the vertical plane with the said members t' t', as shown in Fig. 1, so that the single-tree may be attached and detached with ease.

This gatherer is used in the same manner that the original gatherer is, except that the

driver rides upon the seat L, and by placing his feet upon the teeth he may raise and lower the forward ends of the teeth so that the gatherer will pass over ant and gopher hills, rocks, 5 and other obstructions without difficulty. The seat L may be attached to one of the bars G by means of a cord or small chain, so that when the gatherer is to be reversed it is only necessary for the driver to lift the seat out of 10 the socket in the board N, turn the horses in opposite directions outwardly and pass to the other side of the gatherer, draw the board N through, and replace the seat in the rear socket. The turning of the horses, it will be under- 15 stood, reverses the side gates, E E, and carries the sweep-bars across the head and forces off the accumulation of hay, straw, or other mate- rial, the same as in the original patent.

Having described my invention, I claim as 20 new and desire to secure by Letters Patent—

1. The combination, with the rake A B and side gates, E E, of the slotted sweep-bars G' G', substantially as described.

2. The side gates, E E, pivoted upon the blocks D D, in combination with the stay-plates 25 g g, attached to the posts f f, and pivoted to the head A, substantially as described.

3. The combination, with the head A and plate C, of the sliding board or bar N, having the end stops, P, and the seat L, mounted up- 30 on an upright l, capable of adjustment upon either end of the slide N, substantially as and for the purpose set forth.

HENRY GREBE.
